ABRASIVE DISK SUPPORT

Filed March 3, 1947

FIG. 2

FIG. 3

INVENTOR

William Stever

BY *Maurice A. Crews*

ATTORNEY

UNITED STATES PATENT OFFICE

2,480,886.

ABRASIVE DISK SUPPORT

William Stever, Philadelphia, Pa., assignor to The Budd Company, Philadelphia, Pa., a corporation of Pennsylvania

Application March 3, 1947, Serial No. 732,014

6 Claims. (Cl. 51—197)

1

The invention relates to supports for abrasive discs by a rotatably driven member or head. More particularly, the invention relates to a backing pad for an abrasive disc and to means for firmly connecting such pad and the abrasive disc to a rotating shaft.

Among the objects of the invention is an arrangement which permits of a quick change of abrasive discs while firmly holding the same during the operation so that danger of a disc coming off and causing injury or other damage is eliminated or greatly minimized.

Another object of the invention is a resilient support or backing pad for an abrasive disc which likewise permits of quick exchange in case a pad of another size or resiliency is required or in case the previously used pad is worn out.

Still another object of the invention is a supporting head and a backing pad which is inexpensive and yet sturdy and durable so as to withstand for a long time such rough usage as will occur in metal shops where abrasive discs are widely used.

An object of the invention is also the avoidance of the so-called knife-type head and disc connection as it is disclosed in applicant's Patent No. 1,928,800, "Abrasive apparatus," of October 3, 1933, a type which has been in extensive use for a great many years. This knife-type support is liable to cause injury by the knives and the disc sometimes causes injury by flying off when the supporting head is suddenly stopped.

A more specific object of the invention is the improvement of applicant's devices as disclosed in his Patents No. 2,402,691, "Supporting head for abrasive discs," of June 25, 1946, and No. 2,409,163, "Backing pad for abrasive discs," of October 8, 1946.

With the aforesaid objects in view, the invention resides outstandingly in the combination of a rotatably driven supporting head and a clamping member for the abrasive discs to the head with a resilient backing pad having a central opening, a plurality of radially outwardly extending slots or slits and an annular contact zone between head and supporting disc outwardly of the ends of the slots, the portions of the pad separated by the slots, being engaged by said clamping member and exert a locking effect on the clamping member holding it firmly in place but permitting, nevertheless, the relatively easy removal of the clamping member for the exchange of the abrasive disc.

The aforesaid and other objects and features of the invention will be more easily understood

2

from the embodiment illustrated in the attached drawing and described hereinafter.

In the drawing:

Figure 1 is partly a side elevation of and partly a radial section through an abrasive disc, a supporting or backing pad and a supporting head;

Figure 2 is a plan view of the backing pad shown in Figure 1;

Figure 3 is a perspective view of a disc member 10 for connecting the backing pad with the supporting head; and

Figure 4 is a fragmentary section corresponding to part of Figure 1 but showing head, backing pad and abrasive disc prior to the application or after the removal of the clamping member for holding the abrasive disc.

The head 10, which may consist of an aluminum casting or other suitable metal or material, is generally a body or solid of revolution and has one end interiorly threaded at 11 for connection to a driven shaft (not shown). At the other end, the head has a radially outwardly flaring flange 12, the end face of which is recessed at 13 and has an annular supporting surface 14. An annular projection 15 surmounts the bottom of the recess 13 and is provided with radially outwardly extending sectors 15 forming one-half of a bayonet joint. The other half of the bayonet joint is formed on a disc 16, consisting preferably of sheet metal, having a central opening and having the margin of the opening provided with sector-shaped cutouts 17 leaving between them radially inwardly projecting sector-shaped projections 18. At one end, each projection 18 is formed with an axially outwardly directed ear, flange or tongue 19 for limiting the rotation of the disc 16 relative to the head 10 when the two members are brought into engagement with or are disengaged from each other. It will be noted that the flat middle portion of the disc 16 rests on the surface 14 of the head while its inner portion is dished out so as to fit into the recess 13 of the head 10.

Spacing discs 20 and a backing disc 21 are connected to the outer peripheral portion of the disc 16 by means of countersunk rivets 22. The discs 20 and 21 consist preferably of vulcanized fibre, plastics, or any other material that has the toughness and resiliency required for a backing disc and for the purposes of the invention which are now going to be described.

When not in use, the discs 20 and 21 are substantially plane and their inner portions surrounding a central opening 23 provided in them are radially slotted at 24. These slots or slits

extend from the opening radially outwardly to about the region where the discs 20, 21 contact the metal disc 16. The slots 24 leave between them stiff but somewhat resilient portions or tongues 25, the stiffness and resiliency depending on the material and the thickness of the discs 20, 21 and also on the number of slots. To insure sufficient flexibility of the tongues 25, at least five about equally spaced slits 24 are necessary, while the maximum number of slits is eight to twelve. About eight slits 24, as illustrated, is considered the optimum.

After the discs 16, 20 and 21 are connected with the head, an abrasive disc 26 is placed on the disc 21 and hereupon a mushroom-like screw 27 is screwed with its shank 28 into the matingly screw threaded opening 29 of the head 10. 28 and 29 are multi-threaded with a high pitch so that a relatively small rotative relative movement between screw 27 and head 10 will draw the two together. The head 30 of the screw 27 is approximately lentil-shaped having a spherical outer face 31 and a conical inner face 32. The inclination of the conical face 32 is about equal to the inclination of the dished portion of disc 16.

When the screw 27 is tightened, its conical face 32 bends the central portion of the abrasive disc 26 and the underlying tongues 25 of the discs 20, 21 downwardly. On account of the resiliency of the discs 20, 21, the pressure against the clamp member 27 is maintained during the operation of the device, thereby exerting a locking action and effectively preventing the member 27 from coming loose.

Of course, the construction of the screw 28 and the direction of rotation of the head 10 with its associated parts will be selected so that disc 26 will tend to tighten the screw 27 rather than loosen it.

While the screw 27 may be initially tightened by holding the head 10 with one hand or in a fixture and pressing the palm of the other hand against the spherical surface 30 of the screw, the final tightening may be effected by gripping the outer peripheral portion of the disc 26 and rotating it relative to the head during which motion the member 27 will be taken along by the abrasive disc 26. The removal of the member 26 may be carried out in the reverse sequence of operations, that is, first the screw 27 is loosened by holding the disc 26 and head 10 and rotating the same relative to each other and by then gripping the member 27 with one hand for completely removing it so as to take off the disc 26 and insert a new one.

Merely in passing, it needs to be said that after the removal of the member 27 and the disc 26 backing pad 16, 20, 21 can easily be taken off, reinserted or exchanged on account of the bayonet connection 15', 17, 18, 19. So as to facilitate the holding of the head 10, its inner end may be square or hexagonal or a middle portion thereof may be flattened off at 33 on both sides.

While but one embodiment of the invention is shown and described, modifications and adaptations of the invention will occur to those skilled in the art, and protection is sought for the invention as expressed by the language and the spirit of the attached claims.

What is claimed is:

1. Resiliently flexible backing disc for connection to a driven rotating head and for supporting an abrasive disc, said backing disc having a

thickness and a resiliency sufficient for sustaining the pressure exerted on an abrasive disc supported by it during the use of such abrasive disc, said backing disc surrounding a central opening and more than five radial slots extending from the opening part way toward the outer circumference of the disc leaving between them tongues that are flexible in axial direction.

2. Support for abrasive means comprising a flexible disc and a second disc of smaller diameter, a connection between the second disc near its periphery and a concentric annular portion of said flexible disc, said second disc being adapted for connection to a rotatably driven shaft, said flexible disc having a central opening and a plurality of slits extending radially from said opening at least part way toward the connection between the two discs, the central portion of said second disc being dished away from the plane of said flexible disc so as to permit the flexing of the central portions of the flexible disc separated from each other by said slits.

3. Support for abrasive means comprising a plurality of flexible discs and a substantially rigid disc of smaller diameter than the largest one of said flexible discs, said rigid disc being connected near its periphery to said flexible discs and adapted for connection to a rotatably driven shaft, said flexible discs having a central opening and a plurality of slits extending at least part way toward the connection between the two types of discs, the central portion of said rigid disc being spaced from the plane of the nearest one of said flexible discs so as to permit the flexing of the central portions of the flexible discs separated from each other by said slits.

4. Backing disc for abrasive means comprising a substantially plane flexible disc provided with a central opening and slits extending radially outwardly from said opening part way toward the periphery of the disc to form resilient tongues between said slits, a second disc of smaller diameter than said first disc secured concentrically to said first disc between the central opening and the periphery of the latter and having at least its central portion spaced from the central portion of said first disc, said second disc having its central portion provided with one member of a joint of the type having two members to be engaged with and released from each other by relative rotative and axial movement, the other member of such joint being provided on a rotatably driven member, the resilient tongues formed on said flexible disc between said slits serving as resilient supports for the central portion of an abrasive disc and for a retaining member therefor adapted for removable connection with said driven member.

5. In combination; a backing disc, a supporting head adapted on one side for connection to a rotating shaft and on the other side provided with a central recess, means for connecting said head to the backing disc and with a central removable clamping member for holding an abrasive disc, said backing disc having a central opening and slots extending radially outwardly from said opening part way toward its outer periphery, said head and said backing disc being formed for firm contact with each other in an annular region outwardly spaced from said opening, said clamping member engaging an abrasive disc and the central portion of said backing disc inside of said annular region so as to flex the portions of the backing disc between said slots and thereby

firmly retaining said holding means and the abrasive disc.

6. An abrasive holder and support comprising a supporting head, a resilient plate having a central opening and a plurality of centrally located slits forming between them resilient tongues, an abrasive-holding disc, and screw means for clamping said resilient plate and disc in superposed relation to said rotatable head while resiliently stressing said tongues.
